UNITED STATES PATENT OFFICE.

CORNELIUS A. DAVIS AND HENRY M. WILSON, OF SOMERSET, MASSACHUSETTS.

TROLLEY-POLE CATCHER.

SPECIFICATION forming part of Letters Patent No. 631,361, dated August 22, 1899.

Application filed November 18, 1898. Serial No. 696,787. (No model.)

To all whom it may concern:

Be it known that we, CORNELIUS A. DAVIS and HENRY M. WILSON, citizens of the United States, residing at Somerset, in the county of 5 Bristol and State of Massachusetts, have invented certain new and useful Improvements in Trolley-Pole Catchers; and we do declare the following to be a full, clear, and exact description of the invention, such as will enable 10 others skilled in the art to which it appertains to make and use the same, reference being had to the accompanying drawings, and to the letters of reference marked thereon, which form a part of this specification.

15 This invention relates to electric railways; and its object is to provide an efficient and simple device for preventing the trolley-pole of an electric car from striking the span-wires or brackets when the trolley slips off the wire.

20 It also serves to keep the trolley-pole rope in a taut and trim condition by automatically taking up the slack.

In the drawings, Figure 1 shows the rear end of a trolley-car equipped with our invention. Fig. 2 is a longitudinal vertical section on the line 2 2, Fig. 3. Fig. 3 is a similar section on the line 3 3, Fig. 2. Fig. 4 is a similar section at right angles to Fig. 2, and Fig. 5 shows plan views of the three weights.

30 Attached to the platform of the car, and preferably to the dashboard, is a casing B, preferably rectangular in cross-section. The trolley-pole rope C passes down through a hole b in the top of the casing and is attached to a weight D, which is fitted to slide freely up and down in the casing. The rope is preferably attached to the weight by being rove through a running pulley d fastened thereto and then carried up to the top of the casing,

40 where it is made fast.

In the upper part of the casing are suitable spring-detents E, projecting inwardly and upwardly from recesses in the side walls of the casing. Normally supported on these detents are one or more weights F G, preferably two, as shown. They are adapted to slide freely in the casing and have vertical holes in them for the falls of the trolley-pole rope to pass through.

45 50 In a recess in the back of the casing is secured a spring-catch H, connected by a link

with an eccentric or cam lever or handle I, bearing against the casing. By means of this lever the catch can be drawn back out of the way of the weights F G. At some suitable 55 point, preferably about midway of the casing, two stop-pins K project inwardly from the side walls. The weights D and F are provided with upright grooves d' f in their ends to permit them to pass freely by said pins; but the 60 upper weight G has no such grooves and will be caught and held by the pins when it descends to that point. The lower weight D has also a groove d² in its back edge to enable it to pass up by the catch H. 65

The operation is as follows: The weights F G are normally supported on the detents E at the top of the casing, the detents taking under the weights at points on each side of the grooves f. The weight D is heavy enough 70 to keep a constant tension on the trolley-pole rope, so that the rope is kept taut without pulling the trolley off the wire. The weight plays up and down in the casing as the trolley follows the undulations of the wire. When 75 the trolley slips off and the pole flies up, it carries the weight D up against the weights F G, the edge of the weight D pressing back the detents E, and thereby releasing the weights F G. The three together overcome 80 the tension of the trolley-pole spring and pull down the pole below the plane of the span-wires or the brackets. As they descend the upper weight G is caught by the pins K, as shown in Fig. 3, thus preventing a too severe 85 jar when the weights strike the bottom of the casing. The two lower weights are heavy enough to more than counterbalance the strength of the trolley-pole spring; but the upper weight is desirable in order to give a 90 quick pull on the rope and overcome the momentum of the upwardly-flying trolley-pole. When the trolley has been replaced on the wire, the conductor turns the lever I to allow the catch H to spring inwardly, as shown in 95 Fig. 2. He then lifts the weights by means of the rope until the two upper weights pass the catch H and are retained by it in the position shown in Fig. 2. The rope is then released, and the lower weight at once takes up the 100 slack. The lever I is then turned down to retract the catch from under the weights F

G, which permits them to drop slightly upon the detents E. This completes the resetting of the device.

Having thus described our invention, what we claim, and desire to secure by Letters Patent, is—

1. In a trolley-pole catcher, the combination with a lower weight for automatically taking up the slack of the trolley-pole rope, of an upper additional weight or weights for assisting in pulling down the pole, and spring-detents for said additional weights adapted to be tripped by the lower weight, substantially as described.
2. In a trolley-pole catcher, the combination with a lower weight to be attached to the trolley-pole rope, of one or more upper additional weights for assisting in pulling down the pole, spring-detents for supporting said additional weights, and a catch for temporarily retaining them when raised, substantially as described.
3. In a trolley-pole catcher, the combination with a lower weight to be attached to the trolley-pole rope and having a groove in its edge, of an upper weight, spring-detents for supporting said upper weight, and a spring-catch for temporarily retaining it, said catch

being in the line of the groove in the lower weight, substantially as described.

30

4. In a trolley-pole catcher, the combination with a casing, of spring-detents projecting inwardly near its top, stop-pins projecting inwardly a suitable distance below said detents, and a series of weights adapted to slide in said casing, the lower ones being grooved to pass by said stop-pins, substantially as described.

5. In a trolley-pole catcher, the combination with the casing, of spring-detents near its upper end, a catch just below the detents, stop-pins below the catch, a lower weight having an attachment for the trolley-pole rope, and grooved to pass by the stop-pins and the catch, an intermediate weight having grooves to pass the stop-pins, and an upper weight adapted to be caught by said stop-pins, substantially as described.
